UNITED STATES PATENT OFFICE.

SIDONIE ZELLENKA, OF NEW YORK, N. Y.

ARTICLE OF WEARING APPAREL.

Application filed August 29, 1925. Serial No. 53,217.

This invention is an article of wearing apparel, and, more particularly, relates to lingerie.

There is a growing tendency, particularly among the younger set, to wear as few garments as possible, and the object of the present invention is to provide, in a unitary construction, a thoroughly hygienic, comfortable and efficient article of wearing apparel which may be worn in lieu of several separate garments generally employed. Accordingly, the garment of this invention is constructed to perform the combined functions of a corset, a brassière, a vest, and a chemise.

15 It is of the essence of this invention, that the garment is constituted to hygienically and efficiently perform its intended function better than the separate garments which it displaces by giving proper support without 20 constriction, and allowing perfect freedom of movement of the body with a minimum of body covering.

In order to accomplish these results, my garment is made with a body portion extending 25 from the waistline downwardly well over the hips at both front and back. In the back, the body portion is cut relatively higher, while in the front, the body portion is extended upwardly above the waistline to a point 30 to or directly underlying the bust of the wearer. The body portion is preferably devoid of boning or stays and is made of a material which will not stretch and lose its shape. It is thereby well adapted to perform 35 the functions of a corset. The upward extension of the body portion above the waistline serves to properly support the diaphragm, while those parts of the body portion which overlie the hips produce that 40 smart straight line figure, which is now considered most desirable.

Above the upper edge of the forward part 45 of the body portion and suitably secured thereto by stitching is an upper front section of knitted material so constituted that it will properly conform to and support the breasts without detrimental pressure or constriction. It is suitably reinforced and its function is to support the breasts in a natural 50 manner, giving youthful form thereto.

Elastic sections are incorporated in the sides of the body portion, preferably in the form of darts extending upwardly from the lower edge thereto. The garment is provided with a side opening, which may be

normally closed by any suitable means such as hooks and eyes, snap fasteners and the like.

Features of the invention, other than those specified, will be apparent from the herein-after detailed description and claims, when 60 read in conjunction with the accompanying drawing.

The drawing illustrates one practical embodiment of the invention, but the construction therein shown is to be understood as illustrative, only, and not as defining the limits 65 of the invention.

Figure 1 shows a garment of the present invention in place on a wearer; and,

70 Figure 2 shows the garment laid out flat.

The garment of this invention embodies, generally speaking, three distinct portions, which, for the purpose of concrete description may be referred to as the back portion 1, a lower front portion 2, and an upper front 75 portion 3. One side of the lower front portion 2 is connected to one side of the back portion 1 through an interposed dart 4 of elastic webbing, while a similar dart 5 is secured to the other lateral edge of the portion 2 and is provided along its free edge with hooks or eyes or other suitable fastening means 6, adapted to cooperate with complementary attaching devices 7' formed at the vertical free edge of the back portion 1. 80

As shown best in Figure 2, the attaching devices 6 and 7' extend the full height of the garment at both edges thereof, so that the garment opens along this side to permit it 85 to be put on and taken off.

The back portion 1 is relatively long in a vertical direction. It extends downwardly well over the hips and buttocks and upwardly well above the waistline to a point preferably slightly below the shoulder blades. The front 90 portion 2 extends upwardly from substantially the line of the lower edge of the back portion to a point well above the waistline and directly under the breasts. Both the portions 1 and 2 are formed from fabric not 100 liable to stretch and of sufficient strength to properly support the diaphragm and lumbar regions, and impart to those parts of the body which they cover that substantially straight line form which is now considered smart and 105 desirable.

Positioned directly above the upper edge of the front portion 2 and sewed thereto so as to extend across the entire front of the body and overlie the breasts, is the upper 110

front portion 3. One lateral edge of this front portion is secured to the contiguous edge of the back portion, while the other lateral edge of the front portion carries attaching devices 6 for normally holding the side opening of the garment in closed position. The portion 3 is of knitted material, cut on the bias and set into place in such manner that the two lateral halves of the portion 3 can assume the natural contour of the breasts. Thus, the left hand half of the front section 3, in Figure 2, is composed of four parts 7, 8, 9 and 10, while the right hand portion is similarly composed of four parts 11, 12, 13 and 14. The respective parts are seamed together and the seams are preferably reinforced by tapes 15, which may, in practice, be of the same material as the sections are made of.

The upper edge of the upper center section 3 is provided with a suitable binding 16 of non-yielding material, so as to keep this part of the garment from stretching in a lateral direction. The bottom of the lower front section 2 is also suitably bound and this is also true of the upper and lower edges of the back section 1. The garment is preferably provided with suitable shoulder straps 17 and garter tabs 18.

In practice, the garment is worn as shown in Figure 1 from which it will be seen that the front part 1 extends upwardly well above the waistline designated 19, so that the upper edge of said portion directly underlies the breasts of the wearer. The upper front portion 3 overlies the breasts but because of its inherent yielding characteristics and the formation of it in sections as described, it will support the breasts in natural youthful form and will not press them flat as is so frequently the case with brassières. On the other hand, that portion of the part 2 which lies above the waistline properly supports the front of the body in the region of the diaphragm and the back portion 1 overlies the entire back of the wearer below the shoulder blades and imparts flowing lines to the figure. The elastic gussets 4 bind that part of the parts 1 and 2 below the waistline firmly about the hips without, however, producing uncomfortable constriction.

In practice, the garment is made of washable material, the garters are readily removable from the tabs 18 and no stays or boning are used in the construction. Accordingly, it can be washed as any other garment.

It will be apparent from the foregoing detailed description that the construction of this garment is such that it fulfills the purposes for which several garments have previously been employed and these purposes are fulfilled in a better way than heretofore as there is no overlapping of garments which, if present, produce unsightly wrinkles or ridges in the outer garments. The effect, when the present invention is used, is that of

long relatively straight lines with just that nice suggestion of shaping which is so desirable to present tailoring needs.

As most of the brassières worn in recent years have been quite harmful, due to the fact that they caused the breast cords to become broken, this garment is a timely and important improvement. It holds the bust in its natural form and position, and uplifts the fatigued and broken down breast cords, which brings back the natural, youthful form.

Having thus fully described the invention, what I claim as new and desire to secure by Letters Patent is:

1. A new article of wearing apparel constructed to perform in a single unitary garment the combined functions of a corset, a brassière, a vest and a chemise, and composed of a back part extending downwardly from a point materially above the waist line to overlie the buttocks, a front abdominal part connected at its lateral edges to the back part and extending upwardly from substantially the lower edge of the back part to terminate above the waist line and below the breasts of the wearer, both of said front and back parts being of practically unstretchable material, and a breast part secured to and extending upwardly from the upper edge of the abdominal part to substantially the upper edge of the back part and connected at its lateral edges to said back part, said breast part being of readily flexible knitted material cut on the bias and comprising a plurality of sections seamed together to approximately conform to the contour of the breasts without constriction, and a non-yieldable binding extending transversely across the upper edge of the breast part to preclude stretching of this edge.

2. A new article of wearing apparel constructed to form in a single unitary garment the combined functions of a corset, a brassière, a vest and a chemise, comprising a back portion extending downwardly from a point materially above the waist line to overlie the buttocks, a front abdominal portion connected at its lateral edges to the back portion and extending upwardly from substantially the lower edge of the back portion to terminate above the waist line and immediately below the breasts of the wearer, the front and back portions being of substantially non-stretchable material, and the breast portion secured to and extending upwardly from the upper edge of the abdominal portion to substantially the upper edge of the back portion and connected at its lateral edges to said back portion, said breast portion being of flexible knitted material shaped to cover and conform to the breasts without constriction of the latter.

3. A new article of wearing apparel constructed to form in a single unitary garment the combined functions of a corset, a

- brassière, a vest and a chemise, comprising a back portion extending downwardly from a point materially above the waist line to overlie the buttocks, a front abdominal portion 5 connected at its lateral edges to the back portion and extending upwardly from substantially the lower edge of the back portion to terminate above the waist line and immediately below the breasts of the wearer, the 10 front and back portions being of substantially non-stretchable material, and the breast portion secured to and extending upwardly from the upper edge of the abdominal portion to substantially the upper edge of the 15 back portion and connected at its lateral edges to said back portion, said breast portion being of flexible knitted material and comprising a plurality of sections seamed together to approximately conform to the contour of the breasts and adapted to cover the 20 breasts without constriction.
4. A new article of wearing apparel constructed to form in a single unitary garment the combined functions of a corset, a 25 brassière, a vest and a chemise, comprising a back portion extending downwardly from a point materially above the waist line to overlie the buttocks, a front abdominal portion connected at its lateral edges to the back portion and extending upwardly from substantially the lower edge of the back portion to terminate above the waist line and immediately below the breasts of the wearer, the front and back portions being of substantially non-stretchable material, and the 30 breast portion secured to and extending upwardly from the upper edge of the abdominal portion to substantially the upper edge of the back portion and connected at its lateral edges to said back portion, said breast portion being of flexible knitted material and comprising a plurality of sections seamed together to approximately conform to the contour of the breasts and adapted to cover the 35 breasts without constriction, and a non-yieldable binding extending transversely across the upper edge of the breast portion to prevent stretching of the edge of such portion.

In testimony whereof I have signed the foregoing specification.

SIDONIE ZELLENKA.
